INCENDIARY BULLET

Lewis D. Christie, Bridgeport, Conn., assignor to
 Remington Arms Company, Inc., Bridgeport,
 Conn., a corporation of Delaware

Application May 1, 1942, Serial No. 441,266

2 Claims. (Cl. 102—90)

This invention relates to ammunition and particularly to that type of incendiary bullet, of machine gun caliber, adapted to penetrate the fuel tanks of an airplane and to ignite the gasoline line.

The requisites of an incendiary bullet suitable for this express purpose are exacting. When such bullets are fired from the preferred position of attack, that is to say, on the enemy's tail, the bullet must penetrate the wing structure including the flap surfaces, flap web, rear spar web and possibly other structural members, before reaching the gasoline tanks. Hence, to be effective, it is essential that the sensitivity of the bullet to impact be within a relatively limited range so that the maximum flame will develop at the moment the bullet enters the gasoline tank. Furthermore, it is desirable that such bullets shall perform consistently.

Incendiary bullets of this general type are shown in a co-pending application, Serial Number 439,522, filed April 18, 1942, which discloses a bullet comprising a jacket having a hollow nose portion, an apertured core, an incendiary composition filling both the hollow nose of the jacket and aperture of the core and a suitable heel closure.

It is an object of this invention to provide an improved incendiary projectile constructed and arranged to produce a maximum flame within a predetermined distance after striking the target. A further object is to provide a jacketed incendiary projectile having ignition means in the nose thereof for positively igniting the incendiary composition at the moment of impact. The invention likewise contemplates other improvements in the construction of such bullets which will hereinafter be more fully apparent.

In the drawing:

Fig. 1 is a sectional view of an incendiary projectile embodying the invention.

Fig. 2 is an enlarged sectional view of the bullet shown in Fig. 1 illustrating the probable deformation of the bullet point at the time of primer ignition.

Fig. 3 is a sectional view of a modification of the bullet of Fig. 1.

Fig. 4 is a view of the bullet shown in Fig. 3 at the moment of impact.

As shown in the drawing the incendiary bullet of this invention comprises a jacket 10 of the usual material such as gilding metal having its wall thinned adjacent the nose portion 11, and terminating in a solid body of metal at the tip

12. The jacket is provided with a core 13 consisting of a hard metal such as steel or a suitable hard alloy, having an aperture 14. The core is shorter than the jacket so as to leave a space both in the nose portion and heel portion of the jacket. The space in the heel portion of the jacket is provided for a suitable heel closure which, for example, may consist simply of a lead disc or the combination of a lead disc 15 and a steel disc 16, as shown in Fig. 1, held in position by crimping or turning over the end of the jacket as at 17. The heel closure may also include an inert powdered material such as lead or a mixture of lead and iron oxide as indicated at 18, 15 which is pressed into the heel end of the core aperture 14 to prevent set-back of the incendiary composition and to effect or assist in sealing the incendiary composition 19 against exposure to the powder flame.

20 The aperture 14 of the core is substantially filled with an incendiary composition 19, such as a mixture of powdered magnesium aluminum alloy and barium nitrate in substantially equal proportions. This composition is preferably 25 loaded into the core aperture in two or more increments, the relative size of the increments being susceptible to considerable variation. In accordance with a preferred procedure two increments of charge are used, the first being somewhat larger than the second. Each increment is subjected to a pressure which preferably is not less than about 7000 pounds per square inch, and may be as high as about 28,000 pounds per square inch. Although the particular loading 30 technique described has been found to effect very satisfactory performance it will be understood that variations thereof may be made within the scope of the invention.

Referring to Fig. 1, the end of the core adjacent the nose portion of the jacket is provided 40 with a counterbore 20 concentric with the core aperture 14 and adapted to receive a cup or capsule arranged to contain a percussion sensitive priming composition. Any one of many well known powder igniting ammunition priming compositions may be used. A very convenient cup or container is a standard .22 caliber cartridge case 21. The latter is supported within the hollow nose portion of the jacket by its open end 22, see Fig. 2, which is seated on the shoulder 23 of the counterbore 20. The .22 caliber case is of the rimfire type and has a suitable primer composition 27 in its rim 24. The depth of the counterbore may be such that the rim of the 50 case will project forward into the hollow nose

portion of the jacket so as to be adjacent the wall at its thinned portion 11 and immediately opposite the solid metal tip 12. It will be evident that the .22 caliber case forms, in effect, a closure for the end of the core aperture 14 and consequently when the bullet is charged the incendiary composition 19 substantially fills both the primed case and the aperture of the core. When the bullet is being charged with the incendiary composition it is quite likely that the charging pressures will move the primed case slightly off of the shoulder 23 towards the nose of the jacket but such displacement will not be sufficient to free the open end 22 of the case from the core aperture.

A substantial improvement in the certainty and uniformity of ignition of the incendiary composition is effected by the use of such a housed priming composition, which appears to function as follows: When the bullet strikes the target the force of impact causes the wall of the jacket at its thinner portion 11 to collapse, as shown in Fig. 2, whereby the solid metal tip 12 telescopes rearwardly engaging the head of the primed case and forcing the case towards and into the core. The walls of the case are crumpled and the rim 24 of the case is driven against the end 26 of the core. The rim is then pinched between the end 26 of the core and the solid metal tip 12 of the bullet whereby the priming composition in the rim is ignited and the flame, heat and pressure of its combustion ignites the incendiary composition. The primed case thus constitutes ignition means responsive to the force of impact to positively set fire to the incendiary composition. Bullets formed in accordance with this invention have been found to ignite immediately on striking the target and to acquire a maximum flame at a point corresponding approximately to the location of an airplane gas tank with respect to its usual covering.

A modification of the bullet is shown in Fig. 3. In this form the counterbore 25 is made of such depth that the .22 caliber case may be assembled in the apertured core 13 with the rim 24 of the case seated on the end or face 26 of the core. However, when the bullet is loaded with incendiary composition of substantially the same volume as used in the bullet described above, the charging pressures are sufficient to force the primed case up into the hollow nose of the jacket as indicated by the dotted lines.

As in the former case when the bullet strikes the target the case is forced into the counterbore until the rim of the case is pinched between the end 26 of the core and bullet tip 12, thereby igniting the primer composition and the incendiary composition. In this instance the primed case is partially supported by the compacted incendiary composition in the core and case but apparently the incendiary composition is sufficiently displaced and compressed by the blow to permit the rim of the case to seat on the end 26 of the core as shown in Fig. 4.

This form of the invention is particularly adapted to insure safety when the bullet is being

loaded in the cartridge case. During this process the nose of the bullet is subjected to great pressure which is sufficient under abnormal conditions to deform the jacket. Hence, if the rim of the primed case were to be positively held in close proximity to the thinned wall portion of the jacket the deformation of the wall might ignite the priming composition. However, by providing the end of the core with a relatively deep counterbore 25 the case will be supported in the position shown by the dotted lines, in Fig. 3 only by the compacted incendiary composition and in the event that the nose of the jacket is deformed the primed case is substantially free to move away from the deformation, thus obviating any likelihood of premature ignition of the priming composition. It will be understood that the length and contour of the core can be varied to effect any desired relationship between the core end, the primed shell and the jacket.

Although the use of a .22 caliber case has been shown and described it will be understood that any other priming mixture container may be used, and other variations and modifications made within the scope of the appended claims, which claims are to be broadly construed.

What is claimed is:

1. An incendiary bullet comprising a jacket having a body portion and an integral nose portion, said nose portion comprising a solid metal tip joined to said body portion by an area of minimum cross section in said jacket nose; a one-piece core substantially filling the body portion of said jacket and leaving a hollow nose, said core having an axial aperture extending therethrough; ignition means closing one end of said aperture comprising a primed cartridge case supported within said core aperture and extending into the hollow nose portion of said jacket; an annular recessed shoulder in the front of said core constructed and arranged to form a support for the open end of said primed cartridge and to locate the rim of said primed cartridge in proximity to the thinned area of said nose; and an incendiary composition filling both the aperture of said core and said cartridge case.
2. An incendiary bullet comprising a jacket having a body portion and an integral nose portion, said nose portion comprising a substantially solid tip joined at its base to the body portion of said jacket by a wall section of minimum cross section; a core piece in the body portion of said jacket, said core piece having an aperture and spaced from the base of said tip to provide said jacket with a substantially hollow nose; an incendiary charge in the aperture of said core; ignition means for said incendiary charge comprising an impact responsive device; and means to rigidly support said impact responsive device in said hollow nose immediately beneath the base of said solid tip and in proximity to the wall section of minimum cross section whereby on impact said wall section will collapse and enable the base of said solid tip to abruptly strike said ignition means.

LEWIS D. CHRISTIE.
